UNITED STATES PATENT OFFICE.

JOHN W. CARMAN, OF MADISON, WISCONSIN.

WINDOW-SCREEN.

SPECIFICATION forming part of Letters Patent No. 337,741, dated March 9, 1886.

Application filed November 19, 1884. Serial No. 118,290. (No model.)

To all whom it may concern:

Be it known that I, JOHN W. CARMAN, a citizen of the United States, residing in Madison, county of Dane and State of Wisconsin, 5 have invented certain new and useful Improvements in Window-Screens, of which the following is a specification.

This invention relates to improvements in window-screens in which the screen is mounted upon the spring-actuated roller confined in a case secured upon the side of the sash and open only on its under side, which said screen operates in connection with a bar or plate removably secured upon the window-sill 15 in such a manner that the otherwise free end of the screen may be attached or detached at will from said sill.

One of the objects of this invention is to form such a connection between the edges of 20 the screen fabric and the sash as to prevent insects, &c., from creeping in between the sides of the sash and the edges of the fabric.

A further object is to secure the screen in such a manner that it will be in a vertical 25 line with and lie against the inner edges of the weather-strips of the sash when in an outstretched condition.

Further objects are to automatically clamp the side edges of the outstretched screen 30 against the weather-strips, so as to effectually exclude dust and insects from a room and prevent said edges from drawing or curling, as they will otherwise frequently do in the course of time, to the injury of the fabric and 35 its effective winding upon the roller.

I attain these objects by devices illustrated in the accompanying drawings, in which—

Figure 1 represents a central longitudinal section of a window-screen embodying my invention when the window is down and the screen not in operation. Fig. 2 is a similar view with the window-sash raised and the screen in its outstretched and operative position; Fig. 3, a similar view of an enlarged detail of the same.

Similar letters of reference indicate the same parts in the several figures of the drawings.

A indicates the side frame, and B the sill, of a window; C, an ordinary lower sash, provided 45 on its inner side with a lifting-plate, D; and a b,

respectively, the inner and outer weather-strips for the sides of the sash. On the outer side and lower end of the sash is a case, E, screwed or otherwise removably secured thereto and open on its bottom side, and so arranged 55 with reference to the bottom of the sash that when the sash is in contact with the sill the case will form a close joint with the weather-strip c outside the sash, as shown in Fig. 1. Journaled and concealed in this case is an ordinary 60 spring-actuated roller, d, to which is secured at one end a wire or other open fabric, F, suitable for screen purposes, the opposite end of which fabric is secured to the weather-strip c, which simply rests on the sill and is detachably held down by a spring-catch, G. In other words, the means for forming a stiff edge for catch purposes on the fabric also constitutes a weather-strip for the lower edge of the sash when the sash is down, which said strip is detachable when it is desirable to raise the sash 70 without using the screen. The ordinary rigid weather-strip may also be employed and the strip c rest upon it; but in either case the strip c not only serves to stiffen the fabric, 75 but to close and seal the case, so as to protect the fabric when not in use. One advantage of this construction is, that it dispenses with the necessity of removing the screen for preservation during cold weather, when its use is not 80 desirable.

As will be seen by an inspection of Fig. 2, the above-described arrangement of the roller and strip c maintains the fabric outside of and substantially parallel with the weather-strip 85 b, and hence by this arrangement alone no large aperture occurs between the edges of the fabric and said strip, as is the result when the fabric in its outstretched condition extends at an oblique angle to the strip, as before described. In order, however, to maintain the fabric with its unrolled edges at all times in contact with the side of the strip b, and to effectually exclude dust and insects from creeping in between the edges of the fabric and 90 weather-strip, I have provided a bar, H, for each side edge of the fabric, mounted upon bow or other shaped springs, I, for automatically clamping the fabric to the strip. This bar is preferably of a length less than the 95 100

length of a sash, so that it will operate as hereinafter described when the sash is but partly raised. At the lower end and on the outer edge of this bar is secured a spring, J, 5 impinging against the weather-strip *e* of the outer sash, and secured to this bar at its upper end is an outwardly-curved spring, K, also bearing against the weather-strip *e*. By this arrangement of the spring K it not only 10 serves to press the upper end of the bar inwardly against the fabric, but to form a stop which, in lowering the sash, is engaged by the case, so as to force the bar outwardly from the fabric when lowering the sash from an 15 elevated position, and by this means render the said bar or "jaw," as it may be properly termed, automatic in its operation. While this bar or spring-actuated jaw constitutes an 20 important feature of my invention, and is preferably employed, its omission would not involve a departure from the invention before described.

The invention is not limited to a special 25 form of case, catch device, or spring-seated jaw, for it would be no departure therefrom to employ other forms of parts for performing substantially the same function attributed to these special forms of construction for carrying out this invention.

30 I am aware that screens mounted on rollers and secured directly to the sash or to a bar thereon have had their edges projecting between the weather-strip and a parallel bar actuated to press said edges against the

weather-strip by an eccentric-lever; but such 35 a device is objectionable, because not automatic in its operation.

In another instance an ordinary sash in connection with which no screen is used has had a spring-actuated weather-strip pressing 40 directly against the sash to form a close joint, excluding dust when the window is closed; but a strip of this character and as used could not clamp the edges of a screen, as herein set forth, and, besides, is not designed to be used 45 in connection with a screen; and I therefore make no claim to either of the above devices, for they are essentially different from my invention.

Having described my invention, what I 50 claim, and desire to secure by Letters Patent, is—

1. The screen and the spring-actuated roller thereof, in combination with the strip *b* and a spring actuated bar or jaw for automatically 55 clamping the screen to the strip, substantially as described.

2. The sash, the case secured thereto, the spring actuated roller mounted in said case, and the fabric, in combination with the spring- 60 actuated jaw, the stop K, and a projection on the sash for engaging said stop, substantially as described.

JOHN W. CARMAN.
